UNITED STATES PATENT OFFICE.

HENRY P. MERRIAM, OF NEW YORK, N. Y., ASSIGNOR OF ONE-HALF TO UNITED STATES ORDNANCE COMPANY, OF WASHINGTON, DISTRICT OF COLUMBIA, A CORPORATION OF VIRGINIA.

FUSE FOR PROJECTILES.

SPECIFICATION forming part of Letters Patent No. 770,084, dated September 13, 1904.

Original application filed March 30, 1901. Renewed January 4, 1902, Serial No. 88,444. Divided and this application filed July 21, 1904. Serial No. 217,517. (No model.)

To all whom it may concern:

Be it known that I, HENRY P. MERRIAM, a citizen of the United States, residing at New York, in the county and State of New York, have invented certain new and useful Improvements in Fuses for Projectiles, of which the following is a specification.

The present application is a division of my application, Serial No. 88,444, renewed January 4, 1902.

The present invention relates to improvements in percussion-fuses for projectiles, having for its object to simplify and improve the structure and operation of such fuses, to insure greater safety in the handling and transportation of projectiles, and at the same time maintain the certainty of exploding the shell when it strikes the target.

To this end my invention comprises a suitable fuse-casing carrying a primer, a movably-mounted firing-pin supported in operative relation to the primer, a movably-mounted hammer independent of and in operative relation to the firing-pin, and centrifugally-released securing means normally holding the firing-pin and hammer in inactive position. The hammer is preferably of spherical form, loosely mounted in the fuse-casing so as to be capable of moving forward to actuate the firing-pin upon direct impact of the projectile against an object or upon a lateral or grazing impact of the projectile against the water or other object.

In order that the invention may be fully understood, I will first describe the same with reference to the accompanying drawings and afterward point out the novelty with more particularity in the annexed claims.

In said drawings, Figure 1 is a longitudinal sectional elevation of a fuse embodying my invention. Fig. 2 is a transverse sectional view of the same, taken on the line 2-2 of Fig. 1.

1 is the body of the fuse, externally threaded at 2 and having a head 3 formed with the central threaded reduced portion 4, which is

threaded into the socket or cavity of the body. 1. The socket or cavity 5 of the body 1 is formed with a seat or recess 6, in which normally rests the ball-hammer 7. The hammer 50 7 is surrounded by a spring-band 8, formed with integral spring-fingers 9, which are bent inwardly into engagement with the hammer for maintaining it upon its seat under certain conditions.

10 10 are ports or passages leading through the inner end of the fuse-body 1 for the passage of the flash from the magazines of the fuse (hereinafter referred to) to the bursting charge of the shell.

Within the head 3 of the fuse are mounted the primers and their firing-pins, the magazines of powder which are ignited by the explosion of the primers and flash through the cavity of the fuse-body, and the securing device 65 for holding the firing-pins and the hammer in inoperative position. In this particular form of the fuse shown in the drawings is arranged a series of three powder-magazines 15 at equal distances apart within the fuse-head 70 and three primers 16 of ordinary construction intermediately of the magazines and communicating with the magazines through a train of powder in the annular channel 17, formed between the fuse-body 1 and head 3 and communicating with the powder-magazines 15 through the ports or openings 18 and with the primers through the ports 19. This arrangement is such that if any one of the primers is set off it will flash into and ignite the powder train in the annular channel 17, through which the flash will pass and set off the three magazines of powder, which will flash through the cavity of the fuse and ignite the bursting charge of the shell. The three 80 primers 16 are mounted at the outer ends of the inwardly-inclined sockets 20, in which rest the firing-pins 25, formed with flared heads 25^a and pointed ends 25^b. The primers 16 are held within their sockets at the ends of 85 the recesses 20 by means of the anvil-screws 21. 90 30 is a socket or recess formed centrally

within the fuse-head 3, and 31 is a longitudinally-movable hammer-retaining pin resting loosely within the socket 30 and formed at its inner end with a steel hammer-engaging portion 32. This pin 31 is held normally in the position shown in Fig. 1, in which position it engages the hammer 7 and holds it firmly in its seat 6 in the fuse-body and also the flaring heads 25^a of the firing-pins to hold them in 10 inoperative position in their recesses.

The fuse-head 3 has bored into it a series of three radial channels 40, which are arranged at an angle of one hundred and twenty degrees apart and are located directly over the 15 three powder-magazines 15, above described. The channels 40 meet in the center of the fuse-head 3 and are in open communication with the central recess or socket 30, in which is mounted the hammer-securing pin 31. 20 Mounted within the three radially-extending channels 40 are the three bolts or pistons 45, each one of which is formed at its inner end with an angular projection or nose 46. The 25 projections or noses 46 of the bolts or pistons 45 are identical and form complements of each other, so that when the bolts or pistons are in their inner or hammer-retaining position the noses or projections will mutually interlock—that is, the nose of each bolt interlocks 30 with the nose of one of the others—so that no one of the bolts or pistons can be moved outwardly individually; but all can readily be moved outwardly if they are moved simultaneously. The locking noses or projections 35 upon the inner ends of the bolts or pistons 45 extend at an angle of thirty degrees from the bolts or pistons, and their inner ends are beveled at the same angle, so that the three projections or noses of the bolts will fit snugly 40 together and completely close the recess or socket 30, within which the securing-pin 31 rests, said securing-pin engaging the noses or 45 projections of all of the bolts or pistons and being held thereby into engagement with the hammer and the firing-pins.

In the outer end of each of the radial channels 40 is mounted a small spiral spring 50, which engages the end of the bolt or piston 45 and is held in engagement by means of a 50 thin metal band 51, which surrounds the fuse-head 3.

The operation of the improved fuse may be briefly described, as follows: When the shell equipped with the improved fuse is shot from 55 the gun, it has imparted to it a rotating as well as a forward impulse. The rapid revolution of the shell as it travels through the gun and afterward through the air tends to throw outwardly the series of laterally-extending locking bolts or pistons; but until 60 the centrifugal force exerted upon these parts is sufficient to overcome the friction of the bolts or pistons in their sockets (and this friction is of considerable magnitude while the 65 shell is gaining in velocity in the gun) and

the pressure of their springs and the air-cushions formed in the outer ends of their channels said bolts or pistons will not be moved outwardly. At the moment, however, that the centrifugal force is sufficiently strong 70 to overcome these retarding influences upon the bolts or pistons said bolts or pistons will be thrown outwardly simultaneously in their channels, and this will leave the hammer-retaining pin free to move forward in the fuse-head, which it will do immediately by reason of the fact that the flight of the shell is more or less retarded by the friction of the air, while the inertia of the hammer-securing pin and hammer will tend to move them forwardly 75 in the fuse-body. This tendency to move forwardly in the fuse-body on the part of the hammer is resisted by the spring 89, which engages the hammer; but as there is nothing to prevent the forward movement of the hammer-retaining pin it moves forward in its socket out of the path of the hammer and the firing-pins. The firing-pins also move forwardly in their sockets into engagement with the primers. When the shell strikes the target, 80 the hammer will be suddenly thrown into engagement with the heads of the firing-pins, and one or more of the primers will be fired, and the flash will pass through the powder-train and magazines into the bursting charge 85 of the shell.

While I have shown and described the centrifugally-released securing means in the form of a plurality of interlocking bolts or pistons which are incapable of individual movement, but capable of simultaneous movement, I would have it understood that I do not claim this form of securing means in the present case, since such structure is fully claimed in my above-named parent application, Serial No. 88,444.

In the present application I intend to cover the broad idea of a fuse for projectiles comprising a fuse-body, a primer supported in the fuse-body, a firing-pin movably mounted in the fuse-body in operative relation to the primer, a hammer also movably mounted in the fuse-body independent of and in operative relation to the firing-pin, and centrifugally-released securing means normally holding the firing-pin in its inactive position. I also intend to cover in the present case the stated combination of elements in which the hammer is of spherical form and also such combination in which the centrifugally-released securing means normally hold both the firing-pin and the hammer in inactive position.

Having thus described my invention, what I claim as new, and desire to secure by Letters Patent, is—

1. In combination with a projectile, a fuse therefor adapted to be inserted centrally of the base of the projectile, comprising a tubular casing, a loosely-mounted plunger in the casing, means mounted in the casing adapted 125

to explode a fulminating-cap, and a safety device for normally holding said means to prevent the cap from being exploded, and which when the gun is discharged is unlocked being released entirely by centrifugal force as the projectile is in flight, the plunger moving forward and striking the firing means when the projectile strikes.

2. The combination with a projectile, of a fuse, comprising a casing, a firing-pin, means mounted in the casing engaged by the firing-pin to hold the firing-pin from engagement with the fulminating-cap and when the projectile is in flight to be moved by centrifugal force to release the firing-pin, and means mounted in the casing adapted to strike the firing-pin after the projectile has been impeded in its flight.

3. In a fuse, the combination of a fuse-body, a primer, means mounted in the fuse-body to explode the primer, a plunger movably mounted in the fuse-body independent of the primer-exploding means, and securing means normally holding said primer-exploding means to prevent the primer from being exploded, said securing means being adapted to be released by centrifugal force after the gun has been discharged.

4. The combination of a fuse-body, a primer supported therein, a firing-pin movably mounted in the fuse-body in operative relation to the primer, a hammer also movably mounted in the fuse-body independent of and in operative relation to the firing-pin, and centrifugally-released securing means normally holding the firing-pin in its inactive position.

5. In a fuse for projectiles, the combination of a tubular fuse body or casing adapted to be secured centrally in a projectile, a hammer loosely mounted in the casing, a primer secured in the casing, a firing-pin movably mounted in the casing independently of the hammer and in operative relation to the primer, and centrifugally-released securing means normally hold-

ing the hammer and firing-pin in inactive position.

6. The combination of a fuse-body, a primer supported therein, a firing-pin movably mounted in the fuse-body in operative relation to the primer, a spherical hammer also movably mounted in the fuse-body independent of and in operative relation to the firing-pin, and centrifugally-released securing means normally holding the firing-pin in its inactive position.

7. The combination with a projectile, of a fuse, comprising a casing, a plug mounted in the end thereof, a firing-pin mounted therein, and mechanism mounted in the plug for normally holding the firing-pin from engagement with the cap, and a loosely-mounted spherical plunger in the casing adapted, after the means for engaging the firing-pin has been released and the projectile has been impeded in its flight, to explode the projectile.

8. In a fuse for projectiles, the combination of a tubular fuse body or casing adapted to be secured centrally in a projectile, a hammer loosely mounted in the casing, a primer secured in the casing, a firing-pin movably mounted in the casing in operative relation to the primer, a securing-pin normally engaging the hammer and firing-pin for holding them in inactive position, and centrifugally-released means normally locking the securing-pin against movement, substantially as set forth.

9. In a fuse for projectiles, the combination of a fuse-body, a hammer movably mounted in the fuse-body, a firing-pin also movably mounted in the fuse-body independently of the hammer, and a securing device adapted to independently engage the hammer and firing-pin and hold them in inoperative position, substantially as set forth.
